UNITED STATES PATENT OFFICE.

HOWARD M. DUDLEY, OF PHILADELPHIA, PENNSYLVANIA.

DYEING-MACHINE.

1,327,200.

Specification of Letters Patent.

Patented Jan. 6, 1920.

Application filed November 13, 1917. Serial No. 201,759.

To all whom it may concern:

Be it known that I, HOWARD M. DUDLEY, a citizen of the United States, residing in the city of Philadelphia, county of Philadelphia, and State of Pennsylvania, have invented certain new and useful Improvements in Dyeing-Machines, of which the following is a full, clear, and exact specification.

10 My invention relates to devices suitable for the dyeing of textile fibers and refers particularly to devices suitable for the dyeings of cops, spools and other similar forms of textile fibers in which the fiber is wound 15 upon hollow central members.

One object of my invention is a device suitable for the dyeing of a number of wound fiber forms by the passage of a liquid therethrough.

20 Another object of my invention is a device in which a number of wound fiber forms may be compressed and treated evenly and uniformly by a liquid.

Another object of my invention is a device 25 containing a series of fiber chambers suitable for holding a number of wound fiber forms and having means whereby a liquid may be passed evenly through the fiber.

30 Another object of my invention is a device suitable for the dyeing of wound fiber forms in which the condition of the dyeing treatment may be determined without opening the dyeing receptacle or interrupting the 35 treatment therein.

These and other objects of my invention will be evident upon a consideration of my specification and accompanying drawings.

In the dyeing of wound fiber forms, such 40 as cops, spools and similar forms, in which the fiber is wound upon imperforate hollow members, it is essential that the fiber be maintained in its original position upon the wound form, in order that it may be 45 readily unwound therefrom. As these wound fiber forms do not contain a great length of fiber, a number must be treated simultaneously, and the device must allow the fiber to be packed in a uniform mass.

50 Further, the liquid must be passed through the entire fiber mass uniformly and equally. It is further advantageous to have some means whereby the dyed condition of the fiber may be determined without opening 55 the dyeing chamber or interrupting the dyeing operation.

The device of my invention accomplishes all of the above desired results in a rapid, economical and effective manner.

In the accompanying drawings, illustrating one form of my invention, similar parts are designated by similar numerals.

Figure 1 is a side plan view partly in cross-section.

Fig. 2 is a cross-section through the line 65 2—2 of Fig. 1.

Fig. 3 is a cross-section through the line 3—3 of Fig. 1.

Fig. 4 is a top-plan view of a spider member of the device.

Fig. 5 is a projection of Fig. 6.

Fig. 6 is a broken top-plan view of a foraminous plate.

Fig. 7 is an enlarged vertical cross-section of a series of wide fiber forms mounted 75 upon a core and ready for insertion into a fiber chamber.

Fig. 8 is a vertical cross-section of the testing device.

In the particular form of my device shown 80 in the accompanying drawings, a receptacle is formed by the shell 10, the top member 11 and the bottom member 12 within the shell 10 is a series of fiber chambers 13, 13, 13. The upper portion of the shell 10 has an annular flange 14.

A removable spider member 15 is capable of abutment upon an offset in the flange 14, the screw bolts 16, 16, 16 removably attaching the spider 15 to the shell 10. In alignment with the center of each 90 fiber chamber 13 is a screw bolt 17 meshing with threads in the spider 15. Revoluble upon the bolt 17 is a member 18 having downwardly extended arms 19, 19, capable of abutment upon the annular foraminous 95 plate 20, the member 20 being held from slideable movement along the bolt 17 by the set screw 21 and the shoulder 22 of the bolt 17.

Within each fiber chamber 13 is a removable cylindrical elongated core 23 shown 100 particularly in Fig. 7, the upper end 24 of which is conical shaped and has an opening 25 for the insertion of the hook 26 for removing the core. The lower end 27 of the core 23 is of conical shape with the shoulder 105 28. Capable of abutment upon the shoulder 28 of each core 23 is an annular foraminous plate 29 slideable within the fiber chamber 13.

Below the shell 10 is a spider 30, shown particularly in Fig. 3, this spider 30 being inwardly attached to the flange 31 of the shell 10 by means of screw bolts 32, 32 passing

through openings in the flange 31 and meshing in threads in the spider 30. The spider 30 carries a series of indented members 33, 33, the indents of which are capable of receiving the lower extremities of the cones 27, 27. Each fiber chamber 13 is connected with a testing device, shown in Fig. 8, the interior arrangement of which is similar and proportionate to the interior arrangement 10 of the larger fiber chamber, similar parts being designated by prime members. The member 34 is threaded with the shell 10' and conical end of the core 27 fits in an indent in the member 35 carried by the member 34. 15 The member 36 is threaded with the shell 10' and abuts upon the foraminous plate 20'. The lower end of the shell 10' is removably attached to the pipe 37, carrying the valve 38, by means of the bushing 39. The pipe 20 37 is threaded into the conduit 40 which opens into the chamber 41 of the bottom 12. The upper end of the shell 10' is removably attached to the pipe 42 carrying the valve 43, by means of the bushing 44. The pipe 25 42 is threaded into the conduit 45 which opens above the foraminous plate 20.

The foraminous plates 20 and 29 are similar in construction and comprise a series of concentric annular members 47, 47, connected by the member 48, 48. The annular members 47, 47 comprise a series of triangular members 49, 49 between which are the truncated triangular members 50, 50.

The top member 11 carries a ring 51 to 35 facilitate the removal thereof, and has a contracted cylindrical portion 52 which is removably attached to the pipe 53 by means of the coupling 54. The pipe 53 carries the valve 55 and is connected to the discharge 40 chamber of the pump 56. The bottom member 12 has a contracted cylindrical member 57 threaded to the pipe 58, carrying the valve 59 and connected to the discharge chamber of the pump 56. The pipes 53 and 45 58 are connected by the pipe 60 carrying the valves 61 and 62, the pipe 60 being connected to the pipe 63 opening into the upper portion of the reserve tank 64. The bottom of the reserve tank 64 is connected to the receiving chamber of the pump 56 by means 50 of the pipe 65 carrying the valve 66. The receiving chamber of the pump 56 is also connected to a dissolving tank, not shown, by means of the pipe 67 carrying the valve 68. A pipe 69 carrying a valve 70 connects the receiving chamber of the pump 56 with a source of fresh water supply. A drip pipe 71 carrying the valve 72, opens into the bottom chamber 41.

60 The fiber 100 is wound upon a series of hollow cylindrical members 73, 73 capable of abutment upon, and slidably over the cores 23, 23, as shown in Fig. 7. These members 73, 73 are composed advantageously of thin 65 metal and have notched or indented ends

74, 74, the extended ends being capable of slidably entering the indents of the adjacent member.

Assuming that the device and its contents are as shown in Fig. 1, and the dyeing completed, the operation of the device is as follows:

The member 52 is disconnected from the pipe 53 by means of the bushing 54. The top 11 is then disconnected from the flange 14, by means of the screw bolts 75, 75 which pass through openings in the flange 76 of the top 11 and thread with threaded openings in the flange 14. The top 11 is then removed, and the screw bolt 16 is removed 80 thus allowing the removal of the spider 15 with its described connected members. Each core 23 is then removed from its fiber chamber, carrying with it the dyed fiber. The wound fiber forms are then removed 85 from around the core 23. A foraminous plate 29 is then placed around the core 23 and new fiber forms 100, 100 are also placed around the core 23, care being observed to see that the indents and extensions on the 90 ends of the holders 73 will mesh with one another. The core, with the fiber thereon, is then placed in a fiber chamber, the foraminous plate 20 placed thereon, the spider 15 with its attached members, placed upon the shoulder of the flange 14 and the screw bolt 16 employed to attach the spider 15 with the shell 10. The top 11 is lowered and the member 52 and the pipe 53 attached to each other by the coupling 54. The foraminous plates 20, 20 are forced downwardly by turning the bolts 17, 17, thus forcing downwardly the members 18, 18 and the arms 19, 19 abutting upon the plates 20, 20. The screw bolts 75, 75 are then inserted and screwed inwardly thus attaching the top 11 to the flange 14. At the same time, the foraminous plates 29, 29 are pressed inwardly by turning the screw bolts 32, 32, thus bringing the spider 30 inwardly 110 and forcing the core 23 upwardly.

It will thus be seen that the fiber is compressed from both ends of the mass, thus producing a mass of equal consistency throughout. The testing device is removed 115 from connection with the pipes 37 and 42 by unscrewing the bushings 39 and 44 and the shell 10' withdrawn and loaded with wound fiber forms 100', 100' between the foraminous plates 20' and 29' and compressed by means of the members 36 and 34. The testing device is then replaced and connected with the pipes 37 and 42.

All of the fiber chambers being thus loaded with wound fiber forms, all of the valves are closed with the exception of valves 68, 59, 38, 43 and 61, and the pump started. Dye liquid thus passes from the dissolving tank, not shown, through the pipe 67, the pump 56, the pipe 58, the cham- 130

ber 41, the foraminous plates 29, 29, the fibers 100, 100, the foraminous plates 20, 20, the chambers 46 and 80, and the pipes 53, 60 and 63 into the reserve tank 64. When sufficient dye has been injected into the device, the valve 68 is closed and 66 opened, thus allowing a continuous circulation of the liquid through the device. The liquid, at the same time, passes through the conduit 10 40, pipe 37, foraminous plate 29', the fiber 100', 100', plate 20', pipe 42 and conduit 45. When it is desired to reverse the flow of the liquid, the valves 59 and 61 are closed and valves 55 and 62 opened. Fresh water for 15 washing purposes may be admitted through the pipe 69, after the dye liquid has been drained off through the pipe 71. At any time desired, the condition of the fiber in the larger fiber chambers may be judged by 20 closing valves 38 and 43, removing the testing device and examining its contents, the dyeing operation still continuing.

It is evident that by the combined compression of the fiber from both ends, a more uniform mass is produced than by compression from one end alone, that the projections upon the foraminous plates will allow of a freer passage of the liquid at the ends of the fiber mass and that the reverse flow 25 of the liquid will cause even penetration of the mass.

I do not limit myself to the particular size, number, shape or arrangements of parts as described, all of which may be varied without going beyond the scope of my 30 invention as described and claimed.

What I claim is:—

1. In a dyeing machine, in combination, a receptacle, a series of fiber chambers within 40 the receptacle, an imperforate core within each fiber chamber, a series of imperforate hollow members capable of slidable movement over each core and capable of having fiber wound thereon, means at both ends of 45 each fiber chamber for compressing the fiber and means for forcing a liquid through the compressed fiber mass.

2. In a dyeing machine, in combination, a receptacle, a series of fiber chambers within 50 the receptacle, an imperforate core within each fiber chamber, a series of imperforate hollow members capable of slidable movement over each core and capable of having fiber wound thereon, a foraminous plate at 55 each end of each fiber chamber, means for forcing both foraminous plates inwardly compressing the fiber, and means for forcing a liquid through the compressed fiber mass.

60 3. In a dyeing machine, in combination, a receptacle, a series of fiber chambers having imperforate sides within the receptacle, a removable imperforate core within each chamber, a series of imperforate hollow 65 members capable of slidable movement over

each core and capable of having fiber wound thereon, two removable foraminous plates slidable over each core, means for moving both plates whereby the fiber will be compressed between the imperforate sides of the 70 chamber and the hollow members and means for passing a liquid through the compressed fiber mass.

4. In a dyeing machine, in combination, a receptacle, a series of fiber chambers within 75 the receptacle, an imperforate core within each fiber chamber, a series of imperforate hollow members capable of slidable movement over each core and capable of having fiber wound thereon, means at both ends of 80 each fiber chamber for compressing the fiber and means whereby a liquid may be passed in opposite directions through the compressed fiber mass.

5. In a dyeing machine, in combination, a receptacle, a series of fiber chambers having imperforate sides within the receptacle, an imperforate core within each chamber, a series of imperforate hollow members, the 90 ends of which have a series of indents capable of receiving the corresponding projections of an adjacent hollow member, said hollow members being capable of slidable movement over the core and capable of having fiber wound thereon, two foraminous 95 plates slidable over each core, means for compressing the fiber between the plates and means for forcing a liquid through the compressed fiber mass.

6. In a dyeing machine, in combination, a 100 receptacle, a series of fiber chambers having imperforate sides within the receptacle, a removable imperforate core within each chamber, a series of imperforate hollow 105 members capable of slidable movement over each core and capable of having fiber wound thereon, each hollow member having a series of indents capable of receiving a corresponding series of projections of the adjacent hollow member when they are placed upon the 110 core, two removable foraminous plates slidable over each core, means for moving both plates whereby the fiber will be compressed between the imperforate sides of the chamber and the hollow members and means for 115 passing a liquid through the compressed fiber mass.

7. In a dyeing machine, in combination, a receptacle, a series of fiber chambers having imperforate sides within the receptacle, an 120 imperforate core within each chamber, a series of imperforate hollow members, the ends of which have a series of indents capable of receiving the corresponding projections of an adjacent hollow member, said 125 hollow members being capable of slidable movement over the core and capable of having fiber wound thereon, foraminous top and bottom plates having inwardly extended 130 projections and slidable over the core, means

for moving both plates compressing the fiber, and means for forcing a liquid continuously in opposite directions through the compressed fiber mass.

5. 8. In a dyeing machine, in combination, a receptacle, a top to the receptacle, a bottom to the receptacle, a series of fiber chambers having imperforate sides within the receptacle, a liquid chamber above the fiber chambers, a liquid chamber below the fiber chambers, an imperforate core within each fiber chamber, a removable top; each fiber chamber containing a slidable foraminous bottom, and a series of hollow members slidable 10 over the core and within the chamber, each hollow member being capable of having fiber wound thereon, a slidable foraminous top for each fiber chamber and means for moving the foraminous tops inwardly and retaining them in any predetermined position; means for moving the foraminous bottoms inwardly and retaining them in any predetermined position and means for passing a liquid through the device and the fiber 20 wound upon the hollow members.

9. In a dyeing machine, in combination, a

receptacle, a top to the receptacle, a bottom to the receptacle, a series of fiber chambers having imperforate sides within the receptacle, a liquid chamber above the fiber chambers, a liquid chamber below the fiber chambers, an imperforate core within each fiber chamber, a removable top; each fiber chamber containing a slidable foraminous bottom carrying projecting members, and a series 30 of hollow members slidable over the core and within the chamber, each hollow member being capable of having fiber wound thereon, a slidable foraminous top carrying projecting members for each fiber chamber, and means for moving the foraminous tops inwardly and retaining them in any predetermined position; means for moving the foraminous bottoms inwardly and retaining them in any predetermined position and 35 means for passing a liquid in opposite directions through the device and the fiber wound upon the hollow members.

Signed at New York city, in the county of New York and State of New York, this 40 29th day of October, 1917.

HOWARD M. DUDLEY
